UNITED STATES PATENT OFFICE.

RALPH S. TYLER, OF CLEVELAND, OHIO, ASSIGNOR TO THE CHANDLER AND PRICE COMPANY.

INKING MECHANISM FOR PRINTING PRESSES.

Application filed October 22, 1923. Serial No. 669,987.

The present improvements, relating, as indicated, to printing presses, have more particular regard to printing presses of the so-called platen or Gordon type, the object of the invention being to provide in substitution for the inking disk or disks, wherewith presses of this type are regularly equipped, a square stationary plate from which the ink may be transferred to the form by form inking rolls, just as at present.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a front elevation of a Gordon or platen press constructed in accordance with my invention; and Fig. 2 is a side elevation of the portion of such press which is of present interest.

Of the press, which is of familiar construction, as stated, only those parts which directly co-operate with my novel design of inking mechanism are illustrated in the drawings. Of such parts, the principal ones are the usual form-carrying bed 1, the oscillatory roller frame 3, the arms or links 4 which rock said bed, and the arms or links 5 which oscillate said frame. Carried by frame 3 is the usual inking device for transferring ink to the form on bed 1, such device comprising a series of composition rolls 6, 7 and 8, suitably mounted at their respective ends in saddles 9 and 10 carried by frame 3.

In place, however, of employing a rotatable disk with its lower edge disposed contiguously to the upper side of form 1, so that said inking rolls 6, 7 and 8 may pass from the one to the other, and vice versa, as the frame 3 is oscillated, I have substituted a stationary plate 12 of general rectangular form. This plate is conveniently mounted on the same bracket 13 that has heretofore been utilized to support such disk, inclines at the same angle as such plate, and is disposed with its lower edge, which of course is straight instead of circular, in approximately the same relation

to the bed 1. Accordingly, the aforesaid rolls may pass from said bed onto said plate in the course of their travel upwardly and then back again as they are moved downwardly to their lowermost position which is shown in Fig. 2.

Suitably supported, as by means of arms 15 that project rearwardly from bracket 13, is an ink fountain 16 shown as of standard construction, such fountain rising above and lying in parallel relation to the rear edge of plate 12. Such fountain includes a roll 17 that, upon rotation in a counterclockwise direction, as viewed in Fig. 2, receives on its surface a film of ink from the fountain, as will be readily understood.

Journaled in suitable bearings 18, conveniently provided in the arms 15 which thus support the ink fountain, is a transverse shaft 19, and mounted on each end of such shaft is a spur pinion 20 that engages with a corresponding rack bar 21, suitably guided at its rear end in blocks 22 that project laterally from the plate 12. The forward ends of said rack bars are respectively attached to frames 23 on the order of the saddles 9 and 10, wherein are journaled the corresponding ends of shafts that carry ink rolls 24, 25 and 26. The first two of said rolls rest directly on the surface of plate 12, while the third, which is a distributing roll, rests upon such first rolls and may have, in addition to the rotative movement imparted thereby, a longitudinally vibratory movement.

From the foregoing construction, it will be seen that upon rotation of shaft 19 in a counter-clockwise direction, as viewed in Fig. 2, the frames or saddles which thus carry rolls 24, 25 and 26, will be moved from the position shown in full lines in said figure to that shown in dotted outline, while upon reverse rotation of the shaft, a reverse movement of the rolls is produced. In the position thus shown in dotted outline, the uppermost roll 24, or if desired the riding roll 26, is brought into contact with roll 17 of the ink fountain and receives a predetermined amount of ink therefrom. On the downward travel of the rolls across the plate 12, this ink is distributed by said rolls, as need not be explained in detail, onto the surface of the plate, such distribution being further insured by the action of the rolls on the return movement.

- Rotation of shaft 19 to produce the foregoing results may be obtained in any desired way, but, as shown, I provide a segmental gear 25 that is rotatably mounted on a stud 26 projecting laterally from bracket 13, the teeth of such gear meshing with a pinion 27 on one end of said shaft 19. A link or arm 28 in turn connects said segmental gear with the operating mechanism of the press so that 5 of travel thereof; means for distributing a film of ink on said plate, said means including a second set of rolls reciprocable across said plate, a reciprocable rack connected with said second set of rolls, and a toothed member above said bed for driving said rack, and means independent of said rack for actuating the first-mentioned set of inking rolls. 60
- 10 said gear will be oscillated in proper synchronism with the movement of frame 3. In other words, the rolls 24, 25 and 26 are moved from the position shown in dotted outline in Fig. 2 to the lower edge of the 15 plate and back again during the interval following the passage of the form inking rolls 6, 7 and 8 from off said plate onto the form and their return onto the plate. It will be understood of course that the return 20 movement of the first named or ink distributing rolls may be timed so that they just precede the return movement of the form inking rolls and their downward movement may begin just as soon as the downward 25 movement of said inking rolls begins. 65
- As a result of the foregoing construction, I am able to control the distribution of ink on the inking rolls 6, 7 and 8, so as to meet the varying requirements of different forms. 70
- 30 A square or rectangular plate, moreover, presents a larger area than a circular disk, and better "cutting" action of the distributing rollers on the ink is so obtained. At the same time by having a plain, rectangular 35 plate, whereon the ink is initially distributed, which plate remains at all times stationary, the construction and operation of this portion of the press is much simplified. Such plate, moreover, may be much more 40 readily cleaned than the usual arrangement of disks. 75
- Other modes of applying the principle of my invention may be employed instead of the one explained, change being made as 45 regards the mechanism herein disclosed, provided the means stated by any of the following claims or the equivalent of such stated means be employed. 80
- I therefore particularly point out and distinctly claim as my invention:— 85
- 50 1. In a platen printing press, the combination with the bed and a set of inking rolls adapted to be moved across and in contact with said bed; of an inking plate adjacent 55 the upper edge of said bed and in position to contact with said rolls in the upper range 90
- of travel thereof; means for distributing a film of ink on said plate, said means including a second set of rolls reciprocable across said plate, a reciprocable rack connected with said second set of rolls, and a toothed member above said bed for driving said rack, and means independent of said rack for actuating the first-mentioned set of inking rolls. 95
2. In a platen printing press, the combination with the bed and a set of inking rolls adapted to be moved across and in contact with said bed; of a stationary plate of general rectangular form supported with one 70 edge adjacent to the upper edge of said bed and in position to contact with said rolls in the upper range of travel thereof beyond said bed; and means for distributing a film of ink on said plate, said means including a 75 second set of rolls movable up and down across said plate, a reciprocable rack connected with said second set of rolls at each end thereof and lying along the corresponding side of said plate, and a shaft journaled 80 beneath said plate and provided with pinions in mesh with said racks, respectively, whereby upon rotation of said shaft said second set of rolls will be moved in one direction or the other across said plate. 85
3. In a platen printing press, the combination with the bed and a set of inking rolls adapted to be moved across and in contact with said bed; of a stationary plate of general rectangular form supported with one 90 edge adjacent to the upper edge of said bed and in position to contact with said rolls in the upper range of travel thereof beyond said bed; and means for distributing a film of ink on said plate, said means including a 95 second set of rolls movable up and down across said plate, a reciprocable rack connected with said second set of rolls at each end thereof and lying along the corresponding side of said plate, a shaft journaled beneath said plate and provided with pinions in mesh with said racks, respectively, whereby upon rotation of said shaft said second set of rolls will be moved in one direction or the other across said plate, a third pinion 100 on said shaft, a segmental gear in mesh with said third pinion, and means for oscillating said gear in synchronism with the movement of said first set of rolls. 105

Signed by me, this 18th day of October, 1923.

RALPH S. TYLER.
